UNITED STATES PATENT OFFICE.

GEORGE P. BOSWORTH, OF CENTRAL FALLS, RHODE ISLAND, ASSIGNOR TO HEMPHILL MANUFACTURING COMPANY, OF PAWTUCKET, RHODE ISLAND, A CORPORATION OF RHODE ISLAND.

PATTERN MECHANISM FOR KNITTING-MACHINES.

1,189,046.

Specification of Letters Patent. Patented June 27, 1916.

Application filed October 28, 1914. Serial No. 869,121.

To all whom it may concern:

Be it known that I, GEORGE P. BOSWORTH, citizen of the United States, residing at Central Falls, Rhode Island, have invented 5 certain new and useful Improvements in Pattern Mechanism for Knitting-Machines, of which the following is a specification.

One object of my invention is to provide a pattern drum for knitting machines, which 10 in addition to its step by step forward movement will have at times an oscillating movement.

One result which may be accomplished with a drum of this character is that the 15 pattern may be repeated without using up the pattern surface of the drum to the extent that would be necessary should the drum in this repeating of the pattern be moved forward step by step. Any number 20 of repeating actions may be secured by oscillating the drum. As an example of what may be done with a pattern drum controlled in this way it may be mentioned that the 25 yarn may be changed and alternation of colors introduced into the fabric, say a number of courses of white, then courses of black and then white thus producing a striped pattern, or additional colors may be thrown in as desired.

30 The invention is shown in connection with a stocking machine of this type well known as the "Banner" made under Letters Patent of the United States #933,443, September 7, 1909, though it will be understood 35 that the invention is not limited in this respect as it may be embodied in machines of other types. I do not limit myself to the use of the invention to the formation of 40 striped patterns as the drum moving step by step forward at times and oscillating at other times may be used for producing other variations, it being understood as above stated, that one object is to secure different pattern actions without using up the pattern 45 surface of the drum.

In the accompanying drawings, Figure 1 is a front view of a stocking knitting machine of the "Banner" type with my invention shown in connection therewith. Fig. 50 2 is a plan view of the pattern drum and associated mechanism. Fig. 3 is a side view in the nature of a diagram of a section on

the line 3—3 of Fig. 1; looking from the left and with parts of the mechanism in elevation. Fig. 4 is a detail view of parts 55 shown in Fig. 3 and viewed from the same direction as Fig. 3. Fig. 5 shows links of the pattern chain.

In these drawings, the knitting head 1 and yarn fingers 2, with their operating 60 wires 3 and levers 4, 5, 6 and 7 and pattern drum 8 fixed on the shaft 5', the ratchet wheel e also fixed on said shaft, the sprocket wheel 9 with its sprocket chain B and its ratchet c fixed thereto but loose on the shaft 65 s', the pawl i for driving the ratchet c, the pawl h⁸ for driving the ratchet e, the oscillating quadrant i⁵ carrying said pawls are all constructed and arranged and substantially as in the Hemphill patent and the 70 Banner machine. Further, the engagement of the pawl h⁸ with the ratchet e is controlled by a controller member h pivoted at h³ and having a lug h⁴ to be engaged by lugs on the pattern chain B so that the tail 75 h⁷ of said controller will be lowered to allow the pawl h⁸ to engage the teeth of the ratchet e and thereby turn the drum 8 one step forward. The sprocket wheel 9 with its chain B is moved one step forward in the 80 arrow direction Fig. 3 for each forward, left to right movement of the quadrant i⁵ by the pawl i⁴ engaging the ratchet wheel c which as stated is located on the shaft s' but carries fixed thereto the sprocket 85 wheel 9.

The pattern drum has projections thereon for performing various functions. As an example, it has projections or ribs 4', 5', 6', 7' for controlling the various levers 4, 5, 90 6 and 7 which are pivoted to the frame at 10 and have rearwardly extending arms Fig. 2 to which the yarn finger operating wires 3 are attached. As the drum rotates step by step these lugs or ribs are brought 95 under and lift the forward ends of the levers 4, 5, 6 and 7 in proper predetermined order to control the raising and lowering of the yarn fingers, these feeding under tension of the springs 11 so that the yarns will be 100 changed as desired. Fig. 1 shows that the projection 7' has come beneath the lever 7 and consequently the yarn finger belonging thereto has been raised to take this yarn out of

work, while on the other hand the projection or rib 5' has passed from under the lever 5 allowing this to fall onto the surface of the drum and therefore the yarn finger belonging to this lever is lowered into working position and its yarn has been introduced into the fabric. Now supposing it is desired to reverse the position of these two yarn fingers again. Under ordinary practice an additional projection or rib would be placed on the surface of the drum and this drum would be given another forward step movement and if a number of repeats of this pattern were desired a forward step of the drum would 15 have to be made for each change. With my invention this is avoided for it will be noticed that by moving the drum backward *i. e.* in a direction opposite to that of the arrow in Figs. 1 and 3, the projection 7' will 20 be carried away from under the lever 7 and the projection or rib 5' will be brought under and lift the lever 5 so that yarn belonging to lever 5 will be withdrawn and yarn belonging to lever 7 will be introduced and by 25 oscillating the drum back and forth these yarn fingers will be thrown into and out of work alternately. This action may be continued as long as the pattern is to be repeated. For thus oscillating the pattern 30 drum various means may be provided but in the particular construction shown I employ in addition to the mechanism above described, which includes the pawl h^s and ratchet e , a retracting pawl 12 to engage 35 a ratchet tooth 13 on the speed changing cam p^s which is well known in the Banner machine and Hemphill patents, said cam being fixed to the shaft s' which has the drum 8 fixed thereto as above stated. This retracting 40 pawl is connected with a lever 14 pivoted to the frame at 15 and operated by an arm 16 fixed on the shaft i^s of the quadrant i^s . The pawl rests by gravity upon a bracket 17 suitably fixed to the frame of the machine. When in its forward position its 45 tooth 18 comes in front of the ratchet tooth 13 and therefore on its backward movement driven from the arm 16 it will engage said ratchet tooth and turn the speed changing cam together with the pattern drum backward until the tooth 18 rides up on the cam portion 17' of the bracket 17, thus withdrawing the tooth 18 from the ratchet tooth 13 which thus determines the point at which 50 the backward movement of the pattern drum ceases, this movement however, being sufficient to allow the lever 7 to fall by the withdrawal of its pattern projection 7' and the lever 5 to ride up on the incline 5' and thus 55 upon the top of this pattern lug or rib. The positioning of the retracting pawl is automatically controlled. This may be done by various means but in the particular construction shown I employ a controller 19 having a laterally extending lug 20. This

controller is pivoted on the same pin h^s on which the controller h is pivoted. Its lug 20 is in the path of projections 21 on the pattern chain B so that as these come around they will engage the controller lug 20 and lift the controller and when this is lifted it in turn allows a supplemental controller 22 to operate by gravity and this in turn allows the retracting pawl to fall into the plane for engaging the ratchet tooth 13 for 75 the backward movement of the pattern drum. The supplemental controller lever 22 is pivoted to the frame at 24 and its rear end lies under the retracting pawl 12. Its front end is borne upon by a pin 25 fixed to the controller 19. This controller 19 is pressed normally down by a spring z' and it falls down under this spring pressure when the lug on the pattern chain is moved from under it. 80

When it falls it presses down the forward end of the supplemental controller lever 22 and the rear end of this then lifts the retracting pawl 12 up so that it in its reciprocation will not engage any projection which is on the speed changing cam p^s 90 and no retraction of the drum will take place until the said retracting pawl is allowed to fall and as above stated the falling of this pawl is controlled by the lug 21 on the pattern chain controlling the controller 19. 95

Three of the links of the pattern chain are shown in Fig. 5. It will be observed that these links are those which control the oscillation of the drum. There may be more or less of these in the chain as described. Each of the links shown in Fig. 5 has three projections, two on one side and one on the other and these alternate in position with each other, one occurring first on one side of the chain and the next on the other side throughout the series employed for effecting the oscillation of the drum. These projections on the left of the chain act on the controller h while those on the right of the chain act on the controller 19 so that these are raised or lowered in alternation and therefore, the pawls h^s and 12 work in alternation; the former moving the pattern drum one step forward, while the pawl 12 110 retracts the drum one step backward, thus giving it the oscillating movement as long as links such as are shown in Fig. 5 are passing these controllers. 115

It will be observed that the retracting action of the pawl 12 takes place on the forward left to right stroke of the quadrant i^s , that is to say, the retracting movement takes place on the same direction of stroke of the quadrant on which the forward step movement of the drum takes place, for it will be observed that the pawl h^s pushes the drum forward while the quadrant is going from left to right and also that by reason of the use of the arm 16 and lever 14 the pawl 12 125

- is retracted while the said quadrant is going from left to right and as the strokes of the quadrant bear a certain relation to the revolution of the machine I am enabled by 5 the above timing of the action of the re-tracting pawl to the forward movement of the quadrant to get an even number of courses in different colors. In other words all the changes must take place on the same 10 direction of stroke of the quadrant otherwise for instance we would get more courses of one color than the other and the striping would therefor be uneven but with the mechanism shown, this objection is avoided.
- 15 While I have described the oscillation of the drum in connection with the yarn controlling levers 5 and 7 it will be understood that other changes may be made by bringing into action the other levers in alterna- 20 tion, say for instance the levers 5 and 7 would alternate during the reciprocation of the drum, then the drum would be given a forward movement to bring into action the levers 4 and 6 and then the drum would be 25 oscillated again to alternate the action of these yarn levers 4 and 6. This is an extension of the same principle involved in my invention and this would require placing on the cam p^6 or other part which acts as a 30 carrier therefore other ratchet teeth like the tooth 13.
- The retracting pawl is drawn forward by a spring 26.
- I show on the arm 16 a dog 16^x pivotally 35 mounted and adapted to engage the projection 26 on the cam p^6 as in my application #843,062 filed June 4, 1914. By this as the oscillating quadrant i^5 moves backward, that is while the pawl i^4 is performing its 40 stroke the cam p^6 together with the shaft s' is turned forward one step by the dog 16^x acting on the projection 27 Fig. 4 and this movement may be utilized for controlling desired functions of the machine such as 45 regulating the order of picking as set forth in the application referred to.
- What I claim is:—
1. In combination in a knitting machine, an oscillating quadrant for driving the 50 rotary member thereof for reciprocating knitting, a pattern drum, devices controlled thereby to make changes in the knitting, a ratchet wheel coaxially arranged with and connected with the pattern drum to turn the same step by step forwardly, a pawl to engage and operate said ratchet wheel, said pawl being operated from the quadrant, a controller to determine the times of engagement of said pawl with the ratchet, a 55 pattern chain having projections acting on said controller, a carrier wheel for said chain coaxially arranged with the ratchet and drum, a pawl for retracting the pattern drum, a controller actuated by projections 60 on said pattern chain alternating with the
  - projections first mentioned and means for operating the pawls, substantially as described.
  2. In combination in a knitting machine, a pattern member, devices controlled thereby to make changes in the knitting, a ratchet wheel connected with the pattern member to turn the same step by step forwardly, a pawl to engage and operate said ratchet wheel, a controller to determine the times of engagement of said pawl with the ratchet, a 70 pattern chain having projections acting on said controller, a pawl for retracting the pattern member, a controller actuated by projections on said pattern chain alternating with the projections first mentioned and means for operating the pawls, substantially as described.
  3. In combination in a knitting machine, a rotary member of the knitting head, an oscillating quadrant with connections for driving said rotary member for reciprocating knitting, a pattern member, means for driving the said pattern member forward step by step by the movements of said quadrant, means for driving the pattern 90 member backwardly by the movement of said quadrant and pattern means for determining the times at which said quadrant will drive the pattern member, said pattern member after its backward movement resuming its forward step by step movement, and yarn fingers controlled by said pattern member to make stripes in the fabric by the backward movement of said member, substantially as described.
  4. In combination in a knitting machine, a rotary member of the knitting head, an oscillating quadrant with connections for driving said rotary member for reciprocating knitting, a pattern member, means for driving the said pattern member forward step by step by the movements of said quadrant, means for driving the pattern member backwardly by the movement of said quadrant and pattern means for determining the times at which said quadrant will drive the pattern member, both the forward and backward movement of the pattern member taking place on the same direction of stroke of the quadrant.
  5. In combination in a knitting machine, a pattern member, an oscillating driving member for the rotary part of the machine, a pawl for driving the pattern member forward, a pawl for retracting the pattern 125 member, the first mentioned pawl being connected to the said oscillating member directly, and means interposed between the quadrant and the second pawl for giving it a reverse movement to retract the pattern 130

member, on the same direction of the quadrant movement as operated the first pawl, and means for controlling the pawls to make them operate in succession, substantially as described.

6. In combination in a knitting machine, a pattern member, an oscillating quadrant, a pawl connected with the quadrant for moving the pattern member on the forward 10 stroke of the quadrant, a second pawl to retract the pattern member, an arm on the quadrant shaft, a lever connected with the second pawl and operated by said arm as the quadrant moves forward and means controlling said pawls to render them active or inactive, substantially as described.

7. In combination in a knitting machine, a pattern member, an oscillating quadrant, means for giving said pattern member at 20 times a forward movement as the quadrant swings forward, means for giving the pattern drum a backward movement at times when the quadrant moves forward, means for determining said times of operations and 25 means for giving a forward movement to

the pattern member when the quadrant moves backwardly, substantially as described.

8. In combination in a knitting machine, a pattern member, a ratchet wheel coaxial 30 with and connected with the pattern member, a pawl for operating said ratchet wheel for giving it a step by step forward movement, a pawl for retracting the pattern wheel, means for operating the said pawl, 35 a pattern chain, a carrier therefor coaxial with the pattern member and having projections thereon, a controller for the first pawl operated by the projections, a lever for lifting and lowering the second pawl, and a 40 controller engaging said lever and operated by projections on said pattern chain, substantially as described.

In testimony whereof, I affix my signature in presence of two witnesses.

GEORGE P. BOSWORTH.
